UNITED STATES PATENT OFFICE

HENRY W. PETERS, OF BOSTON, MASSACHUSETTS

FINGER RING AND THE LIKE

Application filed May 11, 1929. Serial No. 362,362.

This invention relates to finger rings and other articles of jewelry, one of the objects being to provide an improved means whereby a stone or other setting can be readily mounted without requiring the services of a skilled jeweler, the means employed for holding the setting in position being simple and efficient and, if desired, forming a part of the ornamentation of the ring or the like.

10 A further object is to provide a means whereby a monogram or other ornamentation can be mounted upon a setting of stone, enamel or the like without requiring the use of rivets or like fastening means for joining the ornamentation to the stone or other setting.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,
30 Figure 1 is a plan view of a portion of a finger ring having the present improvements combined therewith.

Figure 2 is a section on line 2—2, Figure 1.

35 Figure 3 is a perspective view of a retaining member which can be used in connection with the ring.

Figure 4 is an enlarged section on line 4—4, Figure 1.

40 Referring to the figures by characters of reference, 1 designates a flat base which can be a part of a finger ring 2 or other article of jewelry. Soldered or otherwise fastened on this base so as to form a permanent part thereof is a box 3 which can be of any desired contour. In the structure illustrated this box is elliptical. The box is provided at desired intervals with integral ears 4 adapted to extend outwardly therefrom before the setting is placed in position.

A setting 5 of stone, enamel or the like is adapted to be fitted snugly in the box 3 by inserting it through the open outer face of the box. A retaining ring 6 suitably ornamented is then placed within the box so as to rest upon the stone, this ring fitting snugly against the wall of the box and being preferably flush with the outer edge of the box. Said ring may carry any suitable ornamentation such as a monogram insignia or the like indicated at 7 and which is formed with or soldered to the ring. The bottom surface of the monogram or insignia will rest flat upon the exposed surface of the setting 5.

Recesses 8 may be provided within the ring 6, these being so located that after the ring has been placed in position the ears 4 can be bent inwardly and downwardly so as to be seated within the recesses 8 and flush with the exposed surface of the ring 6. With the parts thus assembled it becomes impossible for them to become separated accidentally and at the same time an ornamental setting is provided which heretofore could not be produced except by the use of rivets employed for fastening the monogram, emblem or the like to the stone setting.

While the invention has been shown applied to a finger ring it is to be understood that the same can also be used in connection with pins and the like.

What is claimed is:

1. An article of jewelry including a base, a box integral therewith and having an open face for the reception of a setting, a retaining element fitted snugly within the open face of the box and bearing upon the setting, and means integral with the box and engaging and flush with the outer surface of the retaining means for holding the retaining means and the setting within the box.

2. An article of jewelry including a base, a box integral therewith having an open face, a setting seated on the base and fitted snugly within the box and spaced inwardly from the open face thereof, an ornamental retaining means insertible into the box through its open face and against the setting, and means integral with the box and lapping and flush with the retaining means for holding said

retaining means and the setting within the box.

3. An article of jewelry including a base, a box integral therewith having an open face, 5 a setting seated on the base and fitted snugly within the box and spaced inwardly from the open face thereof, an ornamental retaining means fitted snugly within the open face of the box, said setting constituting a backing 10 therefor, and ears integral with the box, there being recesses in the retaining means for the reception of the ears.

In testimony that I claim the foregoing as my own, I have hereto affixed my signature.
